UNITED STATES PATENT OFFICE.

LOUIS M. COHN AND LEWIS H. WATSON, OF CHICAGO, ILLINOIS, ASSIGNEES,
BY DIRECT AND MESNE ASSIGNMENTS, TO SAID WATSON AND GARRITT
H. OLIVER, OF SAME PLACE.

SELF-ADJUSTING BOTTLE-STOPPER.

SPECIFICATION forming part of Letters Patent No. 415,939, dated November 26, 1889.

Application filed December 10, 1888. Serial No. 293,181. (No model.)

To all whom it may concern:

Be it known that we, LOUIS M. COHN and LEWIS H. WATSON, citizens of the United States, and residents of Chicago, in the county 5 of Cook and State of Illinois, have invented certain new and useful Improvements in Self-Adjusting Bottle-Stoppers; and we do hereby declare the following to be a full, clear, and exact description of the same, reference being 10 had to the accompanying drawings, forming a part of this specification.

This invention relates to that type of bottle-stoppers in which an elastic bulb or bag is adapted to expand within the mouth of a 15 bottle to effect a closure of the same; and the present improvements have for their object to provide a self-adjusting bottle-stopper, embodying the features of cheapness and simplicity of construction, automatic adjustability to form a closure for a large number of 20 different-sized bottle-mouths, combined with ease with which it can be cleansed from any adhering impurities and the avoidance of the disagreeable discharge of the liquid and 25 gaseous spray into the face of the person opening a bottle to which the stopper is applied. We attain such object by the construction and arrangement of parts illustrated in the accompanying drawings, in 30 which—

Figure 1 is a side elevation of our improved self-adjusting bottle-stopper in its normal condition; Fig. 2, a vertical section of the same in position in the neck of a bottle; and 35 Fig. 3 a side elevation of the stopper in an extended condition, ready for insertion in the mouth of a bottle to effect a closure of the same.

Similar letters of reference indicate like 40 parts in the several views.

As represented in the drawings, the stopper consists of a rigid main core or body A, to which the pendent flexible bulb or bag B, that constitutes the stopper, is attached in 45 any suitable manner, preferably by having its upper part molded to shape and stretched over said core and cemented thereto, as indicated in Fig. 2. The pendent bulb B is seamless, as shown; and our present improve-

ment consists in forming the upper portion 50 or neck with outwardly-projecting horizontal flexible ridges b, preferably two or more in number, and of a gradually-increasing size upward, to form a supplementary closure for different sizes of bottle-mouths, and at the 55 same time repress or prevent the tendency of the liquid and gases from discharging in a spray or jet into the face of the manipulator in effecting an opening of a bottle closed by the present type of stopper. 60

C is a vertically-arranged plunger guided in an axial orifice in the core A, as shown in Fig. 2, and having a knob or button C' at top, by which it is manipulated, and a stop-shoulder c, below the core A, to limit its upward 65 movement, its lower end c' being rounded and resting upon the rounded seamless bottom of the flexible bulb B, so that when forced downward by the thumb of the operator it will stretch the flexible bulb into the extended 70 condition illustrated in Fig. 3 from that shown in Figs. 1 and 2. When the plunger is released, it will be forced upward again by the natural elasticity of the bulb. The core A is made of greater diameter than the neck 75 of the bulb B, so as to overhang the same. As thus constructed, its under surface affords a rest for the fingers in manipulating the stopper, as well as a stop to abut against the top of the bottle-neck to limit the entrance of 80 the stopper into such neck.

We claim as our invention and desire to secure by Letters Patent—

A self-adjusting bottle-stopper comprising, in combination, a rigid guide-core A, a pendent seamless bulb B, having a series of horizontal flexible ridges b, gradually increasing in diameter upward, and the plunger C, passing through the core A and provided with a stop-shoulder c, essentially as set forth. 85

In testimony whereof witness our hands 90 this 23d day of October, 1888.

LOUIS M. COHN.
LEWIS H. WATSON.

In presence of—
ROBERT BURNS,
EDWD. A. WEBSTER.
